ELECTRONIC TIMEPIECE FACE

Ken Tang Chow, 430 Minoca Road,
Portola Valley, Calif. 94025

Filed Feb. 16, 1971, Ser. No. 115,931

Term of patent 14 years

Int. Cl. D10—07

U.S. Cl. D42—1 B

The figure is a front elevational view of an electronic timepiece face showing my new design, the face being conventionally of no appreciable thickness.

I claim:

The ornamental design for electronic timepiece face, as shown and described.
